UNITED STATES PATENT OFFICE.

OTTO NUMA WAELETI, OF WATSON, SASKATCHEWAN, CANADA.

RAIL-TIE.

1,138,159.

Specification of Letters Patent.

Patented May 4, 1915.

Application filed December 20, 1913, Serial No. 807,992. Renewed September 30, 1914. Serial No. 864,364.

To all whom it may concern:

Be it known that I, OTTO N. WAELETI, a citizen of Canada, residing at Watson, in the Province of Saskatchewan, and Dominion of Canada, have invented new and useful Improvements in Rail-Ties, of which the following is a specification.

The present invention relates to improvements in ties for railway rails, the object 10 being to construct a metallic tie which shall be simple, strong and durable, and which will embody the desired amount of elasticity.

Another object of the invention is the 15 provision of a metallic tie which may be readily inserted within the roadbed or removed therefrom as desired.

Other objects and advantages of the device will appear as the nature of the invention is more fully disclosed, and in the accompanying drawing, there is illustrated a simple and satisfactory reduction of my improvement reduced to practice, it being understood that various changes in the form, 25 size and construction thereof, may be made without departing from the spirit of the invention or sacrificing any of the advantages thereof.

In the drawing: Figure 1 is a perspective 30 view of a tie constructed in accordance with the present invention, a rail, indicated by the dotted lines, being secured thereon, and Fig. 2 is a central vertical longitudinal sectional view of the same.

The tie may be cast, molded or pressed 35 from a single sheet of material, it being necessary, however, that the said material shall naturally embody a desired amount of resiliency to permit of the tie accomplishing 40 its useful function.

The tie includes a body 1 which is horizontally straight, and which, in reality, provides the top for the tie. The body at its ends and at its center has longitudinal angularly arranged legs 2 which terminate in offset feet 3, the said feet being extended outwardly of the legs. The top of the tie, 45 at a short, but suitable distance from the end legs is formed with transverse depressed portions 4, the same being of a width equal-

ing the width of the base flanges of the rails to be supported upon the tie, and the side walls formed by the depressions or grooves being adapted to frictionally engage with the longitudinal edges of the rails. The 55 lower horizontally straight walls 5 formed by the said grooves or depressions and upon which the rails rest, are extended beyond the side edges of the ties, as indicated by the numerals 6, and these extending portions 60 are provided with openings 7 which are adapted for the reception of securing elements, such as headed bolts 8 and nuts 9 and have the bolts preferably passing through suitable openings in the base flanges of the 65 rails.

From the above description, taken in connection with the accompanying drawing, the simplicity of the device as well as the advantages thereof will, it is thought, be perfectly apparent to those skilled in the art to which such inventions appertain without further detailed description.

Having thus described the invention, what I claim is:

1. A railway tie comprising a top having its sides formed with angularly disposed legs which terminate in outturned feet, the said tie having its top provided with rail receiving depressions, and means for securing 80 the rails upon the tie and within the said depressions.

2. A tie including a top having its side edges adjacent its ends and at its center formed with downturned legs which terminate in outturned feet, the top of the tie adjacent its end legs having rail receiving depressions, the lower walls of the depressions being extended beyond the opposite sides of the tie and having openings for the reception of securing elements, whereby rails may be sustained upon the tie and within the depressions.

In testimony whereof I affix my signature in presence of two witnesses.

OTTO NUMA WAELETI.

Witnesses:

ALICE KITCHEN,
JOSEPH LOKINGER.
